F. H. DOERR,
METHOD FOR SWAGING NEEDLE ARMS AND FULCRUM BARS,
APPLICATION FILED OCT. 29, 1919.

1,394,717.

Patented Oct. 25, 1921.

UNITED STATES PATENT OFFICE.

FRED H. DOERR, OF GRAND RAPIDS, MICHIGAN, ASSIGNOR TO CHENEY TALKING MACHINE COMPANY, OF CHICAGO, ILLINOIS, A CORPORATION OF ILLINOIS.

METHOD FOR SWAGING NEEDLE-ARMS AND FULCRUM-BARS.

1,394,717.

Specification of Letters Patent. Patented Oct. 25, 1921.

Application filed October 29, 1919. Serial No. 334,254.

To all whom it may concern:

Be it known that I, FRED H. DOERR, a citizen of the United States, residing at Grand Rapids, in the county of Kent and State of Michigan, have invented certain new and useful Improvements in Methods for Swaging Needle-Arms and Fulcrum-Bars, of which the following is a specification.

My invention relates to the manufacture 10 of needle arms for use with sound box diaphragms of sound reproducing machines, and has to do especially with the formation of an integral needle arm and fulcrum bar formed by swaging from cold metal.

15 My invention contemplates the formation of a needle arm and fulcrum bar from a single plate of metal of the desired thickness by swaging and forming while the metal is in the cold state, from the initial 20 operation of blanking to the final operation of a completed integral needle arm and fulcrum bar.

One of the objects of my invention is the formation by swaging of a needle arm and fulcrum bar.

Another object is to form an integral needle arm and fulcrum bar for sound box diaphragms of sound reproducing machines.

A further object is to provide a means of 30 making needle arms and fulcrum bars which is inexpensive and expeditious, and to improve such bars for successful commercial use.

On the accompanying sheet of drawings 35 I have shown a series of views of the various steps which may be employed in subjecting a cold piece of metal to swaging to form the bar embodying my invention.

Figures 1 and 2 show in plan and side 40 elevation a blank formed from cold metal of suitable thickness and shape and size.

Figs. 3 and 4 show the effect of the first forming operation wherein it will be noted that the part which is to serve as the needle 45 arm proper has been bent at right angles to the fulcrum bar and also that the needle arm portion has been curved.

Figs. 5 and 6 show the effect of the first 50 swaging operation, which is to straighten the curve formed in the arm of Figs. 3 and 4, so that no cracks or imperfections of any sort will be developed at the length between the needle and fulcrum arm portions.

Figs. 7 and 8 show the needle arm portion 55 flattened so that the form of arm shown

in Figs. 9 and 10 may be blanked from the flattened arm portion.

Figs. 11 and 12 show the finished needle arm and fulcrum with the upper end of the arm bent whereby the upper portion is 60 formed with the usual goose-neck and provided with a bead for attachment to the diaphragm in the usual manner.

In carrying out my invention, metal of 65 suitable quality and thickness is subjected to a blanking operation wherein the blank shown in Figs. 1 and 2 is formed, the parts of the blank being the needle arm part 15 and the fulcrum bar portion 16. The blank is then subjected to a forming operation 70 wherein the part 15 is bent at right angles to the part 16, and in order to prevent breakage near the bead a curve 17 is made at the fulcrum arm portion. The part 15 is then subjected to a swaging operation 75 wherein it is straightened as shown in Fig. 6. Then the arm portion 15 is subjected to a second swaging operation wherein it is flattened as shown in Figs. 7 and 8, the plane of the swaging operation being in a direc- 80

tion of 90° to that necessary to form the parts as shown in Figs. 3 and 4. The flattened portion 15 is then subjected to a forming operation wherein the finished part 15 with the member 18 as shown in Figs. 9 and 85 10 is turned out, the member 18 being utilized to provide a means for connecting the arm to the diaphragm of the sound box. The final operation which may be a forming 90 operation includes twisting of the member 19 through an angle of 90° so that the arm will lie in the plane of the diaphragm to which it is to be fastened and then forming the goose-neck whereby the distance between 95 the fulcrum bar 16 and the point of attachment 20 between the member 18 and the diaphragm (not shown) may be adjusted. If desired, the upper end of the portion 15 may be heated to bend the same through 90° .

However, this heating is not a necessary re- 100 quisite as the bend may be accomplished while the metal is cold. It will be noted that by my invention it is possible to produce a combined needle arm and fulcrum bar from cold metal, which makes possible 105 a reduction of time necessary to produce needle arms and fulcrum bars, increasing the production thereof, decreasing the cost and turning out such articles of uniform

quality and in great quantities. 110

While I have described more or less precisely the details of construction of my invention, yet I do not wish to be understood as limiting myself thereto, as I contemplate changes in form and the proportion of parts and the substitution of equivalents as circumstances may suggest or render expedient, without departing from the spirit of my invention.

10 I claim:

1. The method of making integral needle arms and fulcrum bars which consists in forming a blank having a narrow arm forming portion and a transverse fulcrum forming portion, then developing the relative relation of arm and fulcrum bar by bending, followed by swaging, then flattening the arm, then trimming said blank away to the

required shape and size, and then bending the arm to the ultimate arrangement of 20 form and parts desired.

2. The method of making needle arms integral with fulcrum bars which consists in first punching a blank shaped somewhat like a cross from a metal sheet of suitable 25 thickness, then swaging said blank to turn up the upright with respect to said cross piece, then flattening the upright by swaging same, then blanking the flattened upright to the shape and size desired, then 30 finally bending and twisting the upper end of the upright to provide a portion for attachment to a diaphragm.

Signed at Grand Rapids, Mich., this 7th day of October, 1919.

FRED H. DOERR.
